UNITED STATES PATENT OFFICE

2,121,623

DYNAMO-ELECTRIC MACHINE

Karl Bobek, Falkensee, Germany, assignor to
General Electric Company, a corporation of
New York

Application June 3, 1936, Serial No. 83,378
In Germany June 8, 1935

2 Claims. (Cl. 265—24)

My invention relates to improvements in dynamo-electric machines and particularly to ventilating systems for machines wherein both the armature and field are rotatably mounted.

5 One of the most common applications of dynamo-electric machines having both the armature and field rotatably mounted is in connection with electric dynamometers. These dynamometers are usually of the cradle type and are frequently required to operate over a very wide range of speed. The internal ventilation of such machines is very small for low speeds and frequently is insufficient to prevent overheating unless an external ventilating system is used which

10 is independent of the speed of the machine. In former practice, external ventilators have been used which are attached to the outer rotatable member, but such an arrangement has the disadvantage that the ventilating equipment is carried by the external rotatable member and affects the sensitivity of the machine. In order to eliminate this difficulty, ventilators have been provided which are mounted independent of the external rotatable member and are connected thereto by a flexible connection in the form of a flexible tubing or the like, but such a flexible connection also tends to exert a damping effect on the sensitivity of the machine.

An object of my invention is to provide a dynamo-electric machine wherein both the armature and field structure are rotatably mounted and a ventilating system is provided which substantially does not interfere with the sensitivity or operation of the machine.

35 Further objects and advantages of my invention will become apparent, and my invention will be better understood, from the following description referring to the accompanying drawing, and the features of novelty which characterize my invention will be pointed out with particularity to the claims annexed to and forming a part of this specification.

In the drawing, Fig. 1 is a side elevation of a cradle dynamometer provided with my improved 45 ventilating system, the stationary ventilating casing being shown in section; Fig. 2 is an end elevation of the machine illustrated in Fig. 1; and Fig. 3 is a fragmentary sectional view of a flanged labyrinth joint between the stationary 50 ventilating casing and the rotatable machine frame.

Referring to the drawing, I have illustrated a dynamo-electric machine including an armature 10 provided with a commutator 11 and brushes 12. The armature is mounted on a shaft 13

which is rotatably supported in bearings arranged in upright arms 14 and 15 of a mounting base 16. A field structure including a frame 17 is arranged to cooperate electrodynamically with the armature 10, and also is rotatably or movably supported in bearings mounted in the upright arms 14 and 15 of the mounting base 16. The rotational movement of the field frame structure 17 is limited by a lug 18 secured to the end shield 19 on one end of the field frame 10 structure and extends between two limit stops 20 secured to the vertical arm 15 of the mounting base.

A dynamometer lever arm 21 is secured by a mounting plate 22 to one side of the field frame 15 structure 17. A reverse torque mechanism connects the outer end of the lever arm 21 to a force measuring device. This reverse torque mechanism includes a bar 23 secured to the end of the lever arm 21, and each of the ends of the bar 23 is provided with a notch arranged to engage with pivot pins 24 and 25 of the reverse torque mechanism. If the torque on the field frame 17 is in a counter-clockwise direction, as viewed in Fig. 2, the notch 24' in the bar 23 will 25 engage pin 24 and will exert a downward pull on a link 26 which is connected at 27 to a spring balance scale 28 and a balance mechanism 29. The balance mechanism is pivotally suspended at 29 from a supporting bar 31 mounted upon vertical supports 32, which are secured to the mounting base 16. If the torque on the field frame structure 17 is in a clockwise direction, as viewed in Fig. 2, the notch 24' in the bar 23 will 30 become disengaged from the pin 24 and the bottom 35 of the notch 25' will press upwardly against the pin 25 and exert an upward force upon a link 33. The lower end of the link 33 will engage a pin 34, which is secured to one end of a bar 35 pivotally supported at 36 on a threaded bar 40 36a secured to the mounting base 16. The upward force transmitted to the linkage 33 by the bar 23 will be transmitted through the pivoted bar 35 and a corresponding downward force will be exerted by a pin 37 secured to the other end 45 of the bar 35. The pin 37 will engage the lower portion of a lost motion slot 38 in the link 26 and exert a downward pull upon the spring scale 28 and the balance mechanism 29. In this manner, both clockwise and counter-clockwise torques 50 will give positive indications upon the force measuring device including the spring scale 28 and the balance mechanism 29.

In order to provide for the proper ventilation of the dynamo-electric machine, ventilating open- 55

ings 39 are formed adjacent one end of the field frame 17. A stationary casing 40 is mounted closely adjacent the other end of the field frame 17, and is separated therefrom by a very small clearance 41, just sufficient to permit free turning of the field frame 17 with respect to the casing 40. This casing 40 is formed with an opening in one side thereof which communicates with the interior of the field frame structure 17, and it is supported upon the upright arm 14 by bolts 44 and 45. A cooling and ventilating medium, such as air, is blown through the casing 40 and into the field structure 17, as indicated by the arrows 47 in Fig. 2, by a fan mounted in a casing 48. The fan is driven by an electric motor 49 and both are rigidly secured to the mounting base 16, as shown in Fig. 2.

In certain instances, it may be desired to provide a better seal than that illustrated in Fig. 1, and in such cases a labyrinth flanged seal, as shown in Fig. 3, may be used. This flanged seal includes an axially extending circumferential flange 50 formed around the circumference of the end of the field frame 17. A radially extending flange 51 is formed on the ventilating casing 40 and is provided with an axially extending circumferential groove 52 which is arranged to cooperate and extend about the flange 50. A very small clearance is provided between the flange 50 and the groove 52, in order to provide for free movement of the frame 17 with respect to the casing 40 and to minimize leakage of ventilating medium about the flange 50.

Modifications of the embodiments of my invention, which I have illustrated and described, will occur to those skilled in the art. I desire it to be understood, therefore, that my inven-

tion is not to be limited to the particular arrangements disclosed, and I intend in the appended claims to cover all modifications which do not depart from the spirit and scope of my invention.

What I claim as new and desire to secure by Letters Patent is:

1. A dynamo-electric machine having a rotatable member, a second member movably mounted about said rotatable member and arranged to cooperate electrodynamically therewith, means including a stationary casing having an opening communicating with said movable member for supplying a cooling medium thereto, and a labyrinth flanged seal arranged between said stationary casing and said movably mounted member.

2. A dynamo-electric machine having a rotatable member, a second member having a ventilating opening adjacent one end thereof mounted for limited rotational movement about said first mentioned rotatable member and arranged to cooperate electrodynamically therewith, means connected to said second rotatable member for measuring the torque exerted thereby, a mounting base arranged to rotatably support said dynamo-electric machine, a stationary casing secured to said mounting base and arranged closely adjacent the other end of said second rotatable member and having an opening communicating therewith, a labyrinth flanged seal arranged between said stationary casing and said second rotatable member, and means for supplying a ventilating medium to said dynamo-electric machine through said stationary casing.

KARL BOBEK.
